UNITED STATES PATENT OFFICE

93,673

DESIGN FOR A REFLECTOR

Paul W. Reittinger, Denver, Colo.

Application November 7, 1932, Serial No. 45,803

Term of patent 7 years

To all whom it may concern:

Be it known that I, PAUL W. REITTINGER, a citizen of the United States, residing at the city and county of Denver, and State of Colorado, have invented a new, original, and ornamental Design for a Reflector, of which the following is a specification, reference being had to the accompanying drawing, forming part thereof.

The reflector has its inner surface provided with corrugations concentric with the optical axis and lying in planes perpendicular thereto and has its apex formed from a conical portion extending inwardly and provided with concen-

tric corrugations, the whole forming a highly ornamental design.

In the drawing:

Fig. 1 is a perspective view of the reflector showing the interior thereof;

Fig. 2 is a front elevation of the reflector; and

Fig. 3 is a side elevation thereof.

I claim:

The ornamental design for a reflector, as shown.

In testimony whereof I affix my signature.

PAUL W. REITTINGER.
